UNITED STATES PATENT OFFICE.

EARLE J. R. BEATTIE, OF PROVIDENCE, RHODE ISLAND, ASSIGNEE TO UNIVERSAL OPTICAL CORPORATION, OF PROVIDENCE, RHODE ISLAND, A CORPORATION OF RHODE ISLAND.

EYEGLASS-MOUNTING.

1,270,590.

Specification of Letters Patent. Patented June 25, 1918.

Application filed July 29, 1916. Serial No. 111,983.

To all whom it may concern:

Be it known that I, EARLE J. R. BEATTIE, a citizen of the United States, and a resident of the city of Providence, in the county 5 of Providence and State of Rhode Island, have invented certain new and useful Improvements in Eyeglass-Mountings, of which the following is a specification.

This invention relates to spring clamps to 10 serve as straps or end pieces for all styles and kinds of eye-glasses, which includes spectacles, goggles or other styles of lens mountings, and has for its object to provide a clamp of this character with one or 15 more resilient arms or connecting portions, which are adapted to engage, grip and releasably secure the lens between them, and that without the employment of the usual attaching cement or binding screws, where- 20 by the lens may be readily withdrawn from the mounting and a fresh one inserted when desired.

In practice where lenses of different shapes and sizes are being tried on and 25 fitted to the patient, it has heretofore been necessary with the ordinary type of mounting to remove the screws from the lens straps and end pieces and replace them each time a change is made. This operation 30 takes some time and is often obliged to be repeated many times before the patient is satisfied, and finally accepts the particular style which appears to be best suited to him.

35 In order to facilitate the ready removal and replacement of the lenses, I have provided a spring clamp provided with inwardly turned portions adapted to snap into the screw holes or indentations in the side 40 faces of the lens to firmly yet releasably retain the same in the mounting while being tried on.

This construction of spring strap may be also employed as a permanent connection in 45 attaching the lens to the mounting if desired.

A further object of the invention is to so 50 shape a spring clamp that it may serve as an auxiliary strap or end piece, and to provide the same with means whereby it may be readily attached to these portions, the ends of these auxiliary clamp straps being provided with inwardly turned portions adapted to snap into and project through 55 the screw holes of the strap or end piece and

extend into corresponding holes or indentations in the lens to releasably secure the same in the mounting while being tried on.

With these and other objects in view, the invention consists of certain novel features 60 of construction, as will be more fully described, and particularly pointed out in the appended claims.

In the accompanying drawings:

Figure 1— is a side elevation showing a 65 spring lens strap provided with inwardly turned projections to serve as a spring clamp for engaging the lens.

Fig. 2— is a perspective view showing an end piece member as provided with resilient 70 arms having inwardly turned projections to serve as a spring clamp for releasably engaging the lens.

Fig. 3— shows the arms of the clamp as provided with inwardly turned projections 75 engaging the screw hole in the lens.

Fig. 4— shows the projections in the clamps engaging indentations in the lens.

Fig. 5— shows the extremities of the clamp arms as bent inward to engage the 80 screw hole in the lens.

Fig. 6— is a detail showing a perspective view of another form of my improved clamp as cut from sheet stock and showing a tab on one end for receiving a number. 85

Fig. 7— is an end view of the clamp bent up into operative form.

Fig. 8— is a view showing my improved spring clamp serving as an auxiliary to the ordinary lens strap for releasably securing 90 the lens therein.

Fig. 9— is a view partly in section showing this clamp as applied to the ordinary lens strap with its inwardly turned projections passing through the screw holes 95 in the strap and engaging recesses in the lens to releasably secure the lens in the strap.

Referring to the drawings 10 designates one form of spring lens clamp which may be 100 made in the shape of the ordinary strap 8 as shown in Fig. 1 or in the form of an end piece 9 shown in Fig. 2. The clamp may be attached by any suitable means to the nose bridge portion 11 when used as a strap, or to 105 the usual temple (not shown) when used as an end piece as shown in Fig. 2. The arms 12 of this clamp may be resilient to engage the lens 13 by spring pressure, or the connecting bridge portion 7 of the clamp may 110

also be resilient, and in some cases one arm of the clamp may be resilient and the other stiff and unyielding if desired. The ends of these clamp arms 12 in some cases are provided with inwardly turned projecting bosses or lugs 14, see Figs. 3 and 4 which are secured to these arms by riveting or otherwise. In some cases these inwardly turned projections engage corresponding recesses 15 in the lenses as illustrated in Fig. 4. In other cases these projections enter the screw hole 16 in the lens as illustrated in Fig. 3. Then again in some cases the extremities 17 of these arms may be turned inward as illustrated in Fig. 5 if desired to engage the screw hole 16 in the lens to firmly yet removably secure the lens in position in the mounting.

In some instances it is found quite practical to employ this form of spring strap as a means for permanently securing the lens to the mounting as by its use the usual clamping screw which is continually becoming loosened is done away with, and the lens is more firmly held in position under spring pressure, which prevents it from becoming broken which often occurs by an undue pressure brought to bear upon the lens by setting up the screw too hard. Then again by this construction in the case of breakage the lens may be readily removed and a fresh one positioned therein.

The primary object of my present invention is the use of this spring clamp strap in so-called eye-glass fitting sets, such as those employed by opticians in determining the size and shape of lenses best suited to the different faces to which they are being fitted. In such cases it is often found necessary to remove and replace quite a number of different lenses in the mounting before the proper size and shape is found to satisfy the patient, each change necessitating the removal and replacing of the screw through the strap and lens requiring considerable time and labor.

To simplify this attaching operation, I have provided a spring clamp such as that illustrated in Figs. 6 to 9 inclusive, the same being struck up out of sheet stock as illustrated in Fig. 6 and provided with a pair of arms 18 connected together by a bridge portion 19. The ends of these arms are provided with inwardly extending bosses 20 having rounded or beveled ends 21. A portion of the bridge is cut away as at 22, see Fig. 6, whereby this clamp may be passed over the arms of the usual strap 28 and positioned so that its bridge portion 19 will engage the saddle portion 24 of the mounting, and the bosses 20 will extend through the screw holes 25 in the strap arms to engage the lens. In this way a lens may be readily

positioned in the strap and the bosses will engage the depressions 26 in the lens of the fitting sets to firmly yet releasably hold the lens in the mounting during the trying on 65 operation. The clamp as illustrated in Fig. 6 shows a tab or extending portion 27 which may be provided on one end of this clamp for the purpose of receiving an identifying character. This auxiliary clamp may also 70 be fitted to engage the usual end piece (not shown).

By the term eye-glass mounting in the specification and claims I mean any device adapted to support lenses on the face of the 75 wearer.

By bridge portion in the specification and claims I mean that portion connecting the two spring arms of the clip and by nose bridge I mean that member 11 connecting 80 the two lenses.

I have shown and described an illustrative embodiment of my invention but I desire it to be understood that although specific terms are employed they are used in a generic sense 85 and not for the purpose of limitation, the scope of the invention being defined by the appended claims.

I claim:

1. An auxiliary spring clamp for eyeglass 90 mountings comprising a pair of resilient arms connected by a bridge member, one or both of said arms being provided with inwardly projecting members for engaging corresponding holes in the lens by spring 95 pressure, and the ends of said projecting members being beveled to facilitate their ready entrance to and withdrawal from said holes.

2. An auxiliary spring clamp for eyeglass 100 mountings comprising a bridge member having oppositely disposed resilient arms, projections extending inwardly from one or both of said arms for extending through the screw openings of the usual lens straps for 105 engaging corresponding apertures in the lens.

3. An auxiliary spring clamp for eyeglass 110 mountings comprising a pair of opposing resilient arms connected by a bridge 110 member, said arms being provided with inwardly turned portions adapted to extend through the screw openings of the usual lens strap, the same being provided with an opening in the bridge portion to permit of its being positioned on the mounting strap.

In testimony whereof I affix my signature in presence of a witness.

EARLE J. R. BEATTEY.

Witness:

JOSEPH ROSENBLATT.
